UNITED STATES PATENT OFFICE.

JACINTO P. MONTLLOR, OF NEW YORK, N. Y.

SHOE AND SLIPPER.

1,051,615.

Specification of Letters Patent. Patented Jan. 28, 1913.

Application filed June 5, 1911. Serial No. 631,348.

To all whom it may concern:

Be it known that I, JACINTO P. MONTLLOR, a subject of the King of Spain, and a resident of New York city, in the county of New York and State of New York, have invented certain new and useful Improvements in Shoes and Slippers, of which the following is a specification.

This invention relates to shoes or slippers, 10 and more particularly to light, soft shoes suitable for athletic purposes, boat wear, bathing, and for other purposes where a shoe of this character is desirable.

Among the objects of the invention are to 15 make such a shoe of simple, inexpensive, and attractive construction, to thoroughly protect the sole of the foot from bruising or abrasion, to guard against slipping, and to render the shoe properly flexible for quick 20 movement.

The invention consists in the construction herein illustratively shown and described and more particularly pointed out in the claims.

25 In the accompanying drawings illustrating certain preferred embodiments of the invention: Figure 1 is a side view of the shoe; Fig. 2 is a bottom plan view of the sole; Fig. 3 is a cross-section through the 30 sole, lining and part of the upper, showing one of the stitches which hold the sole in shape loosened; Fig. 4 is a transverse section taken at another point; Fig. 5 is a detail showing a piece of the braided rope 35 from which the sole is formed; Fig. 6 is a perspective view showing the arched pins in the relation which they may occupy when in position in the sole; Fig. 7 is a plan view of a heel; Fig. 8 is a fragmentary side elevation of a shoe provided with such a heel; Fig. 9 is a side view of another form of shoe 40 embodying the invention, with certain features not disclosed in the preceding forms; Fig. 10 is a cross-section through this shoe; Fig. 11 is a perspective view of another 45 form of shoe.

The sole 10 is formed of braided or woven hemp cord which is coiled into the proper shape, in which it is retained by transverse 50 stitches 11 and longitudinal stitches 11^a, preferably also of hemp cord, which pass horizontally back and forth through the sole, through the middle of the several courses of the cord forming the sole.

55 The upper 14 may be of canvas or other suitable light construction. It may be low

as shown, or high. It and a lining 15, which overlies the sole and may be of canvas or other suitable material, are secured to the sole by the same marginal stitches 16. 60 These stitches are formed close together, so as to produce, in effect, a continuous binding concealing the upper part of the sole and the junction between the sole and the upper. There may be any suitable number 65 of rows of these stitches. At the toe and heel there are preferably a considerable number of rows so as to afford a suitable reinforcement and finished appearance at these regions.

I preferably insert transversely arched supports into the sole in advance of the heel, to afford a certain arch to the sole. In the particular construction illustrated these supports are in the form of U-shaped pins 17, 70 formed of stiff material and provided with notches or barbs 18 to prevent them coming out. These pins are inserted from opposite sides of the sole, and may overlap each other as shown.

75 In the form of the invention shown in Figs. 7 and 8, I provide the shoe with a heel 19 separately formed from braided cord coiled into the proper shape and secured by transverse stitches 20, similar to the stitches 11. The heel is preferably so formed that entrances and exits of the stitches 20 are directly under the entrances and exits of the stitches 11. The heel is secured to the sole by means of 80 stitches 21, which pass through the heel, up along the sides of the heel and sole, through the sole, down along the sides of the sole and heel, and through the heel again. The junction between the heel and the sole is concealed by finer marginal stitches 22 set close 85 together to constitute a species of band or binding. These stitches contribute materially to the securing of the heel, also.

90 A shoe of the character just described is excellent for all athletic purposes. The sole is non-slipping, and when closely formed is not readily penetrated by water. At the same time it affords a certain degree of 95 ventilation, and does not "draw" the feet like rubber soles. The lining protects the foot from any roughness in the rope; and the marginal stitching unites the three parts of the shoe together, that is, the sole, lining and upper, and affords a desirable finish for 100 the shoe.

In Figs. 9 and 10 I have shown a shoe

similar to that of Fig. 8, but possessing certain additional features of importance. In this construction I have provided the sole with a facing extending around its 5 edges. This facing practically consists of a strip or strips of leather or the like. In the particular construction illustrated it consists of a section 30 extending around the sides of the forward and major portion 10 of the sole and a strip 31 extending around the sides and the rear portion of the sole and the heel. The two strips may be overlapped or joined in any suitable manner, at the region of the arch, as indicated 15 at 32. Obviously, the facing strip may be formed in one piece. The strip is preferably secured to the margins of the sole and heel by means of the horizontal stitches 11, 11^a and 20 which hold the sole and heel 20 in shape. The heel stitches 21 also preferably pass through and over the heel portion of the strip, so as to contribute to the retention thereof. Such a facing or binding strip has numerous advantages in connection 25 with the particular form of sole which I employ. It not only materially adds to the appearance of the shoe, giving the effect of a leather sole, but also greatly strengthens the construction. In conjunction with the 30 stitches which pass through it and through the sole and heel it binds and holds the coiled courses of the cord in a compact manner and insures against spreading of the sole and heel. In connection with this form 35 of shoe I have shown straps 25 and 26 secured to the sides of the shoe at the arch and adapted to pass over the instep, being provided with a buckle 33 for adjustably connecting their ends. The buckle is preferably 40 located at one side of the shoe, so as to avoid undue pressure upon the instep. To this end the strap 26 may be longer than the strap 25. The straps are shown as provided with enlarged end portions 27 which 45 are secured to the sides of the upper by means of stitches 28. The straps may pass through guide-loops 29 on the upper to prevent them from slipping downward on the instep. These straps afford means, either in 50 conjunction with the pins 17 or independently of the use of such pins, for drawing up the sole of the shoe beneath the arch of the foot.

Fig. 11 shows a modified form of the last- 55 illustrated shoe. Here the straps 25^a and 26^a, corresponding to the straps 25 and 26 of Figs. 9 and 10, are continued in the form of lacings 25^b and 26^b, which coöperate with

customary hooks 40 on the upper part of the shoe. The lower part of the shoe may 60 be laced by a separate lacing 41. Obviously, the lacings 25^b and 26^b may be each in one piece with its strap, or the lacings may be formed separately and secured to the ends of the straps. The lacings may be made long 65 enough to tie around the ankle, so as to afford, with the straps, an efficient brace to the foot.

The straps 25 and 26 or 25^a and 26^a may be of the same material as the upper 14 or 70 of other material, as desired.

What I claim is:

1. In a shoe, the combination of a sole formed of cord coiled into sole shape, 75 stitches passing transversely and longitudinally through the sole and holding the same in shape, an upper, a lining overlying the sole, and marginal stitching securing the sole, lining and upper together and constituting a continuous band or binding 80 concealing the upper part of the sole and the junction between the upper and sole.

2. A shoe having a sole formed of cord coiled and secured in the proper shape, a 85 separate heel formed of cord coiled in the proper shape and held by horizontal stitching passing through the heel, and means securing the heel to the sole.

3. A shoe having a sole formed of cord coiled and secured in the proper shape, a 90 separate heel formed of cord coiled into the proper shape and held by horizontal stitching passing through the heel, stitching securing the heel to the sole, and means concealing the junction between the sole and 95 heel.

4. In a shoe, the combination of a sole formed of rope coiled and secured in proper shape, and transverse arched supports passed through the sole in advance of the heel 100 portion thereof.

5. A shoe having a sole formed of cord coiled and secured in sole shape, a separate heel formed of cord coiled and secured in the proper shape, and a leather facing extending 105 around the edges of the sole and heel.

6. A shoe having straps secured to the sides thereof at the arch and having lacing continuations, and means on the front of the shoe with which said lacing continuations 110 coöperate, whereby the act of lacing draws up the arch of the shoe.

JACINTO P. MONTLLOR.
